UNITED STATES PATENT OFFICE.

LARS O. GRONDAHL, OF PITTSBURGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Substitute for application Serial No. 590,856, filed September 27, 1922. This application filed April 15, 1924. Serial No. 706,664.

My invention relates to railway traffic controlling apparatus, such for example as automatic signaling systems, and has for an object the provision of apparatus of this character comprising direct current electromagnetic devices operated from sources of alternating current through the medium of rectifiers.

The present application is a continuation 10 of my co-pending application filed on the 27th day of September, 1922, Serial No. 590,856, for railway traffic controlling apparatus, in so far as the subject matter common to the two is concerned.

15 I will describe certain forms of apparatus embodying my invention, and will then point out the novel features thereof in claims.

In the accompanying drawings, Figs. 1^A, 20 1^B and 1^C constitute, when placed end to end in the order named, a diagrammatic view showing one form of railway signaling system embodying my invention, these views being referred to collectively hereinafter as Fig. 1. Figs. 2^A and 2^B constitute, 25 when placed end to end in the order named, a diagrammatic view showing a modification of the system shown in Fig. 1, and also embodying my invention, these two views being referred to collectively hereinafter as Fig. 2. Fig. 3 is a detail view, partly diagrammatic and partly in elevation, showing 30 one form of signal and one arrangement of controlling circuits therefor, suitable for use in either of the systems shown in Fig. 1 or Fig. 2. Fig. 4 is a detail view showing one form of indicator suitable for use with the systems shown in Figs. 1 and 2.

Similar reference characters refer to 40 similar parts in each of the views.

Referring first to Fig. 1, the reference characters 2 and 2^a designate the track rails of a railway along which traffic normally moves in the direction indicated by the arrows. 45 These rails are divided by insulated joints 3 into a plurality of blocks A—B, B—C, * * * G—H, and located at the entrance end of each block is a signal designated by the reference character S with an exponent corresponding to the location. 50 Each of these signals is of the semaphore type, and with the exception of S^r and S^g

each signal is adapted to indicate stop, caution or proceed, according as the semaphore is in the horizontal, the inclined or the vertical position. Signal S^r has but two positions, and is provided with a special control as will be explained hereinafter. Signal S^g also has but two positions.

Each block is provided with a track circuit comprising the track rails of the block, a source of current, and a track relay. Considering block A—B, for example, the track relay is designated R^A and is of the direct current type, having a winding connected across the rails at the entrance end of the block. The source of current for this block comprises a transformer T², the primary of which is connected with a transmission line M, which is constantly supplied with alternating current from a suitable source, such as a generator J. The secondary of transformer T² is connected with a rectifier K², which converts the alternating current from transformer T² into direct 75 current. The direct current terminals of the rectifying device K² are connected with the track rails adjacent the exit end of block A—B through a pole-changer P^B, which is operated by signal S^B for the next 80 block in advance.

The rectifier K² may be of any suitable type, such for example as the device shown in Figs. 7, 8 and 9 of an application for Letters Patent of the United States filed by Lars O. Grondahl on January 7, 1925, No. 1,111. Briefly described, this device comprises four rectifying units 4, 5, 6 and 7, each of which in turn comprises a body consisting of a metal having an electronically 85 conducting compound of the metal formed thereon and integral therewith, such body constituting in and by itself a unidirectional current carrying device or asymmetric conductor. The body may, for example, be 90 copper with cuprous oxide formed thereon. One feature of such a rectifier is that it transmits an alternating current wave form without substantial distortion, that is, it transforms an alternating current into a 95 uni-directional current each pulsation of which is substantially one-half of an undistorted sinusoidal wave. The four units are 100 so connected between the transformer sec-

ondary and the pole-changer P^B that when the left-hand terminal of the secondary of transformer T^2 is positive, current will flow from that terminal through rectifier unit 4 to the pole-changer P^B and back through unit 7 to the right-hand terminal of the secondary; whereas when the right-hand terminal of the secondary is positive, current will flow therefrom through unit 6 to the pole-changer and back through unit 5 to the left-hand terminal of the secondary. The result is that the current supplied to the pole-changer and so to the track circuit is a uni-directional current which fluctuates 10 in value with the alternations in the electro-motive force in the transformer secondary. It will be seen, therefore, that the direct current relay R^A readily responds to the current thus supplied to the track circuit. 15 Pole-changer P^B is operated by signal S^B and is reversed while this signal is moving between the stop and the caution position. It follows that when signal S^B indicates stop, current of one polarity, which I 20 will term "reverse" polarity, is supplied to the rails of block A—B, whereas when signal S^B indicates caution or proceed current of the opposite polarity, which I will term "normal" polarity, is supplied to the rails 25 of the block A—B. Relay R^A is a polarized relay, in that it is provided with a contact 69 which is closed when the relay is supplied with current of normal polarity, but is open 30 when the relay is supplied with current of reverse polarity. 35

Referring now to Fig. 3, the signal S^A comprises a semaphore 87 pivotally mounted at 87^a on a supporting mast or post 88. This semaphore is biased to the "stop" or horizontal position as shown in solid lines, but may be moved to the "caution" or inclined position, and to the "proceed" or vertical position, as indicated in dash lines, by means of an electric motor 89 through the medium of 40 suitable operating mechanism which I will now describe.

The operating mechanism comprises an arm 90 pivotally mounted at point 90^a and operatively connected with the semaphore 87 through suitable means indicated by the dash line 91. The arm 90 is moved by chains 92 and 93, which chains are in turn driven by the motor 89 in the direction indicated by the arrows. The chain 92 operates over a sprocket wheel 94 and another sprocket wheel 95, the first of these wheels being driven by the motor through suitable reduction gearing which is not shown in the drawing but which is indicated by the dash line 96. The chain 93 operates over a sprocket wheel 97 and another sprocket wheel which is not shown in the drawing, but which is mounted directly behind the wheel 95 and is attached to the same shaft 50 as the latter wheel. The chains 92 and 93

are provided with rollers 98 which project laterally from the chains to engage with a fork 99 pivoted at point 99^a in arm 90. Two pairs of rollers are provided for each chain, the two pairs on each chain being disposed 70 at diametrically opposite points on the chain. The fork 99 comprises three parallel prongs (only one of which is shown), the first and second of which coact with the rollers 98 on chain 92 and the second and third of 75 which coact with the rollers 98 on chain 93.

The fork 99 is controlled by an electro-magnet 100, preferably of a slow-releasing type, through a toggle mechanism 101 in the arm 90, the control being such that when the magnet 100 is energized, the fork is held rigidly in the position shown with respect to arm 90, that is, in a projected position in the path of rollers 98, but is free to swing upwardly to a retracted position out of the path of these rollers when the magnet is de-energized. It follows, then, that when magnet 100 is energized, and motor 89 drives the chain 92, one pair of rollers 98 on this chain will engage the fork 99 and so elevate arm 90 and semaphore 87 to the intermediate or caution position, in which position the rollers pass out from under the fork and the fork is caught and held by a latch 102. This latch is pivoted to the framework of the signal mechanism and is biased to the position in which it is shown by a spring 102^a. If now the motor 89 is again operated, the fork 99 will be caught by one of the pairs of rollers on chain 93, so that the arm 90 and semaphore 87 will be elevated to the highest or proceed position, where the rollers will pass out from under the fork and the fork will be caught and held by a latch 103. This latch is biased to engaging position by a 95 spring 103^a. In this position a knob 121 on arm 90 opens a contact 117. The semaphore will then remain in this position until magnet 100 becomes de-energized, whereupon the fork 99 will swing upwardly with respect to arm 90 and so become disengaged from latch 103, so that the arm 90 and semaphore 87 will drop to their lowest positions, as shown in the drawing. 100

Operating current is supplied to the motor 89 and holding magnet 100 of signal S^A from a transformer T' through a rectifying device K' which is identical to the rectifying device K^2 hereinbefore described, and the supply of this current is controlled by track relay R^A . 115

The operation of the signal S^A and of its controlling circuits is as follows:

When the relay R^A is de-energized, the motor 89 and magnet 100 are de-energized, so that the semaphore 87 is in the stop position and all of the other parts of the signal are in positions in which they are shown in Fig. 3. I will now assume that pole-changer P^B is operated to energize relay R^A in reverse 120 130

direction, that is, in such direction that the polarized armature contact 69 remains open. The closing of the neutral armature contacts of this relay cause magnet 100 to become energized, the circuit being from the rectifier K', through wires 8 and 9, front contact 10 of relay R^A, wires 11, 12 and 104, contact 105—106, wire 107, magnet 100, wires 108 and 13, front contact 14 of relay R^A, and wires 15 and 15^a to the rectifier K'. Motor 89 becomes energized at the same time, its circuit being from rectifier K' through wires 8 and 9, contact 10, wires 11, 12 and 109, contact 120—110, wire 112, motor 89, wires 113 and 13 contact 14, and wires 15 and 15^a to rectifier K'. Motor 89 and magnet 100 both being energized, the arm 90 is then raised by the rollers 98 on chain 92, so that the semaphore 87 is moved to its intermediate or caution position. When this position is reached contact 120—110 is opened and contact 119—110 is closed by the cam 111, so that the supply of current to the motor 89 is discontinued.

If, now, pole-changer P^B is reversed so that relay R^A becomes energized in normal direction, that is, in such direction as to close its polarized armature contact 69, motor 89 will again become energized, its circuit then being from the rectifier K', through wires 8 and 9, contact 10, wires 11 and 16, contact 69, wires 17 and 116, contact 117, wire 118, contact 119—110, wire 112, motor 89, wires 113 and 13, contact 14, and wires 15 and 15^a to rectifier K'. The motor is thus again caused to operate, so that the chains 92 and 93 are again operated. Since magnet 100 is still energized, arm 90 is raised by the rollers on chain 93. Shortly after the arm 90 leaves its intermediate position, contact 115—106 becomes closed and contact 105—106 becomes opened, and the magnet 100 is then energized through the following circuit: from rectifier K', through wires 8 and 9, contact 10, wires 11 and 16, contact 69, wires 17 and 114, contact 115—106, wire 107, magnet 100, wires 108 and 13, contact 14, and wires 15 and 15^a to rectifier K'.

When the arm 90 reaches its highest position, wherein semaphore 87 indicates "proceed", it opens contact 117 thereby discontinuing the supply of current to motor 89.

When signal S^B is in the proceed or the caution position, pole-changer P^B is in such position as to supply current of normal polarity to relay R^A, so that signal S^A then indicates proceed. When signal S^B is in the stop position, however, pole-changer P^B is reversed, so that current of reverse polarity is supplied to relay R^A, with the result that contact 69 of this relay is open and signal S^A indicates caution. Signal S^A, of course, indicates stop when section A—B is occupied.

It will be observed that the electro-magnetic elements of signal S^A are a motor 89 and a magnet 100, both of which are designed for operation by direct current. The current supplied to these elements by rectifier K' is a uni-directional current each pulsation of which is substantially one-half of an undistorted sinusoidal wave, and so it will be apparent that these elements will readily respond to such current. I have found that when the motor and magnet are designed for operation by a direct current of 10 volts, they will operate in the same manner if alternating current at 20 volts is supplied to rectifier K' by transformer T'.

The apparatus associated with block B—C is exactly the same as that associated with block A—B. The same thing is true of block C—D, except that this block contains a siding switch L, and this switch operates a contact device 28 for shunting the tract circuit when switch L is open. This switch is open, as shown in the drawing, so that contact device 28 is closed, whereby relay R^C is de-energized and signal S^C indicates stop. Signal S^B accordingly indicates caution.

Switch L is provided with an indicator I, the circuit for which passes from rectifier K', through wires 8 and 29, contact 30 of relay R^A, wire 31, contact 32 of relay R^B, wire 33, contact 34 of relay R^C, wire 35, lamp or operating mechanism of indicator I, and wires 36 and 15^a to rectifier K'. Indicator I requires the supply of current to this circuit in order to give an indication that switch L may be opened, and so it will be seen that the indicator will give this indication only when there is no train between point A and point D. One form of indicator which may be employed is illustrated diagrammatically in Fig. 4, this indicator comprising a magnet 122 controlling an armature 123 which in turn actuates a miniature semaphore 124. The magnet 122 is designed for operation by direct current, and so it responds readily to the pulsating uni-directional current supplied thereto by the rectifier K'.

Block D—E is provided with two track sections D—X and X—E, each of which has its individual track circuit. The track circuit for section X—E is the same as that for block A—B, in that it comprises a transformer T¹⁰ and rectifier K¹⁰, a pole-changer P^E, and a polarized relay R^X. There is no signal at point X, however, and so the supply of current to tract section D—X is controlled by relay R^X. When signal S^E indicates proceed or caution, relay R^X is energized in normal direction, as shown in the drawing, and current of normal polarity is then supplied to section D—X through the following path: from rectifier K⁸, through contact 19, wire 20, neutral contacts 21 and 22 in multiple, wire 23 to rail 2, and from rail 2^a, through wire 24, polar

4
 contact 25 and wire 66 to rectifier K^8 . Contacts 21 and 22 are connected in multiple in this circuit to reduce the contact resistance in the circuit, this being a standard and well understood expedient in signaling practice. When signal S^E indicates stop, however, relay R^E is energized in the reverse direction so that current flows from the rectifier through contact 25 and wire 24 to rail 2^a, and from rail 2, through wire 23, contacts 21 and 22 in multiple, wire 20, contact 19 and wire 67 to the rectifier K^8 . This current is of reverse polarity. When section X—E is occupied by a train, relay R^E is de-energized and the rails 2 and 2^a of section D—X are then bridged through wire 23, back point of contact 22 and wire 24, so that relay R^D is likewise de-energized. The control of signal S^D by relay R^D is the same as the control of a signal S^A by relay R^A .

A crossing bell is provided at point X, and this bell is controlled by an interlocking relay Q. The supply of current to relay Q and crossing bell N is furnished by a transformer T^6 and a rectifier K^9 . Magnet 45 of relay Q is controlled by relay R^D , through a circuit which passes from rectifier K^9 , through wires 41 and 42, contact 43, wire 44, magnet 45, and wire 40 to rectifier K^9 . Magnet 27 of relay Q is controlled by relay R^E , the circuit being from rectifier K^9 , through wire 38, contact 26, wire 37, magnet 27 and wires 39 and 40 to rectifier K^9 . The circuit for bell N is from rectifier K^9 , through wires 41 and 46, back contact 47 and wire 48 (or back contact 51), wire 49, bell N, and wire 50 to rectifier K^9 . It will be seen, therefore, that when a train moves in the normal direction of traffic, bell N will begin to ring as soon as the train passes point D and will stop ringing when the train passes point X. When a train moves in opposition to traffic, the bell will begin to ring when the train passes point E and will stop ringing when the train passes point X. Relay Q and bell N are designed for operation by direct current, so they are operated efficiently by the pulsating uni-directional current supplied to them by rectifier K^9 .

Considering block E—F, the control of signal S^E by relay R^E is the same as the control of signal S^A by relay R^A , but the supply of current to the track section of this block is governed in a special manner which will be pointed out hereinafter. Signal S^F at point F is a train order signal which is manually controlled and has only two positions, namely, stop and proceed. The track circuit for block F—G is the same as for block A—B. The polarity of the current supplied to the track circuit for block E—F is governed by a pole-changer P^E operated by signal S^E , and this current is supplied from a transformer T^{12} and a rectifier K^{12} . When signal S^E is

in the stop position, as shown in the drawing, current of reverse polarity is supplied to block E—F, the circuit being from rectifier K^{12} , through wires 52 and 53, pole-changer P^E , wire 54, contact 55 of relay R^E , wire 56, front point of contact 57, wire 58 to rail 2^a, and from rail 2, through wire 59, polar contact 60, wire 61, pole-changer P^E , and wires 62 and 63 to rectifier K^{12} . This current being of reverse polarity, signal S^E indicates caution. When signal S^E is moved to the proceed position, pole-changer P^E is reversed, so that current of normal polarity is then supplied to relay R^E , and signal S^E consequently indicates proceed. When a train occupies block F—G, relay R^E is de-energized, and the rails of block E—F are then bridged by wire 58, back point of contact 57 of relay R^E and wire 59, so that signal S^E indicates stop.

Block G—H is the last block of the system, and so signal S^G for this block is a two-position signal indicating stop and caution. For this reason signal S^G is provided with a caution circuit only, current for which is supplied by a transformer T^{14} and a rectifier K^{14} . Track circuit current for block G—H is supplied by a transformer T^{15} and a rectifier K^{15} , there being no pole-changer involved in the track circuit for this block.

When block G—H is occupied by a train, current of reverse polarity is supplied to the rails of block F—G, so that relay R^F is energized in reverse direction. The polar contacts 60 and 55 of this relay then operate to connect the rectifier K^{12} directly to the rails of block E—F, but in reverse direction, so that signal S^E then indicates caution, regardless of the position of the train order signal S^F . In other words, under this condition pole-changer P^E is eliminated from the track circuit for block E—F. The reason for this is to insure that signal S^E shall indicate caution whenever signal S^G indicates stop, so that automatic protection is afforded at all times.

The system shown in Fig. 1 is what is known as a polarized track circuit system in that current of one polarity or the other is supplied to the track circuit for each block according to traffic conditions in advance of such block. In Fig. 2 I have shown a non-polarized track circuit system, that is, a system in which current of one polarity is supplied to the track circuit.

Referring now to Fig. 2, and particularly to block A—B, the rails of this block are supplied with uni-directional current from transformer T^2 and rectifier K^2 , there being no pole-changer associated with the track circuit. Signal S^A is controlled by track relay R^A and also by a line relay W^A . The caution indication circuit for signal S^A is from rectifier K^2 , through wires 8 and 9, contact 10 of relay R^A , wire 11, operating

mechanism of signal S^A , wire 13, contact 14 of relay R^A , and wires 15 and 15^a to rectifier K' . The proceed indication circuit for this signal is from rectifier K' , through wires 8 and 9, contact 10 of relay R^A , wire 16, contact 69^a of line relay W^A , wire 17, operating mechanism of signal S^A , wire 13, contact 14 and wires 15 and 15^a to rectifier K' . In other words, the circuits for this signal are the same as the circuits for signal S^A in Fig. 1 except that the polar contact 69 on relay R^A in Fig. 1 is replaced by a neutral contact 69^a on line relay W^A in Fig. 2. It will be seen, therefore, that when track relay R^A is energized and line relay W^A is de-energized, signal S^A will indicate caution, but that when both of these relays are energized the signal will indicate proceed.

Line relay W^A is controlled by contact 81 operated by signal S^B , the circuit being from rectifier K^3 , through wires 79 and 80, contact 81, wire 82, contact 83 of track relay R^A , line relay W^A , and wires 84, 85, 86 and 88 to rectifier K^3 . Contact 81 is closed when signal S^B indicates proceed or caution, but open when this signal indicates stop. It follows, therefore, that signal S^A indicates proceed when signal S^B indicates proceed or caution, but signal S^A indicates caution when signal S^B indicates stop.

Line relay W^A is designed for operation by direct current, and so it operates efficiently on the uni-directional current supplied by rectifier K^3 .

The apparatus associated with block B—C is the same as that associated with block A—B, and the same thing is true of block C—D, except that this block is provided with a switch L and with contacts 28 as in Fig. 1^b, for opening track relay R^C when the switch is reversed. As shown in the drawing, this switch is in normal position, but relay R^C is opened due to the presence of a train V in block C—D, so that signal S^C indicates stop and signal S^B indicates caution. Switch L is provided with an indicator I, which is controlled as in Fig. 1 by track relays R^A , R^B and R^C .

Block D—E is provided with two track sections D—X and X—E, but the track relays R^D and R^E for this block are both neutral or non-polarized relays. Line relay W^D is controlled by contact 81 operated by signal S^E , and so the only function of relay R^E is to supply track circuit current to track section D—X when the relay is energized and to bridge the track rails of this section when the relay is de-energized. It will be observed that when a train occupies track section D—X signal S^D will indicate stop because track relay R^D is de-energized, and when a train occupies section X—E signal S^D will still indicate stop because relay R^E is de-energized with the result that relay R^D is still de-energized. When a train

occupies block E—F signal S^D will indicate caution, because relay R^D is energized but the line relay W^D is de-energized owing to the fact that contact 81 associated with signal S^E is open.

In this instance point F is the end of the system, and so signal S^E is a two-position signal, indicating stop and caution only.

One important feature of apparatus embodying my invention is the fact that it enables a direct current signaling system to be converted into an alternating current signaling system without changing or replacing any of the electro-magnetic devices, such as track relays, line relays, signal mechanisms, and switch indicators. In other words, to make the change just referred to, it is only necessary to eliminate the batteries and to substitute for such batteries, transformers and rectifying devices.

Another important feature of my invention is that the rectifying devices K have unity power factor, so that the direct current relays, motors, magnets, etc. are operated at maximum efficiency, that is, there is no phase displacement of voltage and current in the rectifying devices.

Although I have herein shown and described only certain forms of apparatus embodying my invention, it is understood that various changes and modifications may be made therein within the scope of the appended claims without departing from the spirit and scope of my invention.

Having thus described my invention, what I claim is:

1. The method of converting a direct current railway traffic controlling system into a system using alternating current energy which consists in replacing the batteries by sources of alternating current and rectifiers each rectifier comprising a body consisting of a metal having an electronically conducting compound of the metal formed thereon and integral therewith, said body constituting in and by itself a uni-directional current carrying device.

2. Railway traffic controlling apparatus comprising traffic governing devices designed for operation by direct current, a transmission line carrying alternating current, and copper oxide rectifiers for supplying uni-directional current to said devices from said transmission line.

3. Railway traffic controlling apparatus comprising traffic governing devices designed for operation by direct current, a transmission line carrying alternating current, and full wave copper oxide rectifiers for supplying uni-directional current to said devices from said transmission line.

4. Railway traffic controlling apparatus comprising traffic governing devices designed for operation by direct current, a transmission line carrying alternating cur-

rent, and rectifiers interposed between said transmission line and said devices and each comprising a body consisting of a metal having an electronically conducting compound of the metal formed thereon and integral therewith, said body constituting in and by itself a uni-directional current carrying element.

5. Railway traffic controlling apparatus comprising traffic governing devices designed for operation by direct current, a transmission line carrying alternating current, and rectifiers interposed between said transmission line and said devices and each comprising a copper electrode with cuprous oxide formed thereon.

6. Railway traffic controlling apparatus comprising traffic governing devices designed for operation by direct current, a transmission line carrying alternating current; and full wave rectifiers interposed between said transmission line and said devices, each rectifier being made up of a plurality of bodies, and each body comprising a metal having an electronically conducting compound of the metal formed thereon and integral therewith, such body constituting in and by itself a uni-directional current carrying element.

30 7. Railway traffic controlling apparatus comprising traffic governing devices designed for operation by direct current, a transmission line carrying alternating current; and full wave rectifiers interposed between said transmission line and said devices and each comprising a copper electrode with cuprous oxide formed thereon.

8. Railway traffic controlling apparatus comprising traffic governing devices designed for operation by direct current, a transmission line carrying alternating current, and means interposed between said transmission line and said devices and comprising asymmetric conductors capable of transmitting the alternating current wave form changed by reversing every other half wave but without substantial distortion.

70 9. Railway traffic controlling apparatus comprising traffic governing devices designed for operation by direct current, a transmission line carrying alternating current, and means interposed between said transmission line and said devices and comprising asymmetric conductors for transforming said alternating current into a uni-directional current each pulsation of which is substantially one half of an undistorted sinusoidal wave.

80 10. Railway traffic controlling apparatus comprising traffic governing devices designed for operation by direct current, a transmission line carrying alternating current, and means interposed between said transmission line and said devices and comprising asymmetric conductors for trans-

forming said alternating current into a uni-directional current each pulsation of which is substantially one half of an undistorted sinusoidal wave, whereby said devices may be operated from an alternating voltage which is substantially equivalent to the direct current voltage for which the devices are designed. 70

11. Railway traffic controlling apparatus comprising traffic governing devices designed for operation by direct current, a transmission line carrying alternating current, and rectifiers interposed between said line and said devices and each comprising opposed asymmetrically conducting units, each unit comprising a body consisting of a metal having an electronically conducting compound of the metal formed thereon and integral therewith, such body constituting in and by itself a uni-directional current carrying element. 75

12. In a direct current railway traffic controlling system operated by continuously rectified alternating currents, a rectifier comprising opposed asymmetrically conducting units, each unit comprising a body consisting of a metal having an electronically conducting compound of the metal formed thereon and integral therewith, such body constituting in and by itself a uni-directional current carrying element. 80 90

13. In a direct current railway traffic controlling system operated by continuously rectified alternating currents, a rectifier comprising opposed asymmetrically conducting units, each unit comprising a body consisting of a metal having an electronically conducting compound of the metal formed thereon and integral therewith, such body constituting in and by itself a uni-directional current carrying element permitting minimum distortion of the alternating current wave form. 100

14. In a direct current railway traffic controlling system operated by continuously rectified alternating currents, a rectifier comprising opposed asymmetrically conducting units capable of transmitting the alternating current wave form changed by reversing every other half wave but without substantial distortion. 110 115

15. Railway traffic controlling apparatus comprising traffic governing devices designed for operation by direct current, a transmission line carrying alternating current, and rectifiers interposed between said line and said devices and each comprising a solid body consisting of two substances permanently in mutual contact whereby the devices are never on open circuit, each said body constituting in and by itself a uni-directional current carrying element. 120 125

16. In a direct current railway traffic controlling system operated by continuously rectified alternating currents, a rectifier com- 130

- prising a solid body consisting of two substances permanently in mutual electrical contact, said body constituting in and by itself a uni-directional current carrying device.
- 5 17. In a direct current railway traffic controlling system operated by continuously rectified alternating currents, a rectifier comprising opposed units each made up of a solid body consisting of two substances permanently in mutual electrical contact, each said body constituting in and by itself a uni-directional current carrying device.
- 10 18. Railway traffic controlling apparatus comprising traffic governing devices designed for operation by direct current, a transmission line carrying alternating current, and a circuit for each device including said line and a body consisting of a metal having an electronically conducting compound of the metal formed permanently thereon, each said body constituting in and by itself a uni-directional current carrying element.
- 15 19. In combination, a railway traffic controlling device designed for operation by direct current, a source of alternating current, and a circuit including the two and a body consisting of a metal having an electronically conducting compound of the metal formed permanently thereon and integral therewith, said body constituting in and by itself a uni-directional current carrying element.
- 20 20. In combination, a source of alternating current, four units each comprising a body consisting of a metal having an electronically conducting compound of the metal formed thereon and integral therewith, each said body constituting in and by itself a uni-directional current carrying device, means for connecting the metal of the first unit and the compound of the second unit with one terminal of said source, means for connecting the metal of the third unit and the compound of the fourth unit with the other terminal of said source, a railway traffic controlling device, means for connecting the compound of the first unit and the compound of the third unit with one terminal of said device, and means for connecting the metal of the second unit and the metal of the fourth unit with the other terminal of said device.
- 25 21. Railway traffic controlling apparatus comprising a signal actuated by a motor designed for operation by direct current, a transmission line carrying alternating current, and a full wave rectifier interposed between said line and said motor and comprising a plurality of bodies each consisting of a metal having an electronically conducting compound of the metal formed thereon and integral therewith, and each said body constituting in and by itself a uni-directional current carrying device.
- 30 22. Railway traffic controlling apparatus comprising a signal actuated by a motor designed for operation by direct current, a transmission line carrying alternating current, and means interposed between said line and said motor and comprising asymmetric conductors capable of transmitting the sinusoidal wave form of the alternating current without substantial distortion.
- 35 23. Railway traffic controlling apparatus comprising a signal provided with a holding magnet designed for operation by direct current, a transmission line carrying alternating current, and a full wave rectifier interposed between said line and said magnet and comprising a plurality of bodies each consisting of a metal having an electronically conducting compound of the metal formed thereon and integral therewith, each said body constituting in and by itself a uni-directional current carrying device.
- 40 24. Railway traffic controlling apparatus comprising a signal provided with a holding magnet designed for operation by direct current, a transmission line carrying alternating current, and means interposed between said transmission line and said magnet and comprising asymmetric conductors each capable of transmitting one half of the sinusoidal wave form of the alternating current without substantial distortion.
- 45 25. Railway traffic controlling apparatus comprising a signal provided with an operating motor and a holding magnet both designed for operation by direct current, a transmission line carrying alternating current, and a full wave rectifier interposed between said line and said signal elements and comprising a plurality of bodies each consisting of a metal having an electronically conducting compound of the metal formed permanently thereon and integral therewith, each said body constituting in and by itself a uni-directional current carrying device.
- 50 26. Railway traffic controlling apparatus comprising a signal provided with an operating motor and a holding magnet both designed for operation by direct current, a transmission line carrying alternating current, and means interposed between said line and said signal elements and comprising asymmetric conductors capable of transmitting the sinusoidal wave form of the alternating current without substantial distortion.
- 55 27. Railway traffic controlling apparatus comprising an electro-magnet designed for operation by direct current, a traffic controlling device governed by said magnet, a transmission line carrying alternating current, and a full wave rectifier interposed between said line and said magnet and comprising a plurality of bodies each consisting of a metal having an electronically conducting com-

15. compound of the metal formed thereon and integral therewith, each said body constituting in and by itself a uni-directional current carrying element.
16. 28. Railway traffic controlling apparatus comprising an electro-magnet designed for operation by direct current, a traffic controlling device governed by said magnet, a transmission line carrying alternating current, and means interposed between said line and said magnet and comprising asymmetric conductors each capable of transmitting one half of the sinusoidal wave form of the alternating current without substantial distortion.
17. 29. Railway traffic controlling apparatus comprising the traffic rails and traffic governing devices associated therewith arranged for operation by low voltage direct current as customary, an alternating current transmission line, and transformers and low-resistance rectifiers connected between said line and said traffic governing devices for furnishing said low voltage direct current to said devices, each rectifier comprising a body consisting of a metal having an electronically conducting compound of the metal formed thereon and integral therewith, said body constituting in and by itself a uni-directional current carrying element.
18. 30. Railway traffic controlling apparatus comprising the traffic rails and traffic governing devices associated therewith arranged for operation by low voltage direct current as customary, an alternating current transmission line, and transformers and low-resistance rectifiers connected for full wave rectification between said line and said traffic governing devices for furnishing said low voltage direct current to said devices, each rectifier comprising a body consisting of a metal having an electronically conducting compound of the metal formed thereon and integral therewith, said body constituting in and by itself a uni-directional current carrying element.
19. 31. Railway traffic controlling apparatus comprising the traffic rails and traffic governing devices associated therewith arranged for operation by low voltage direct current as customary, an alternating current transmission line, and a transformer and four double opposed rectifiers connected between said line and each traffic governing device for furnishing said low voltage direct current to such device, each rectifier comprising a body consisting of a metal having an electronically conducting compound of the metal formed thereon and integral therewith, said body constituting in and by itself a uni-directional current carrying element.
20. 32. Railway traffic controlling apparatus comprising the traffic rails and traffic governing devices associated therewith arranged for operation by low voltage direct current as customary, an alternating current transmission line, and rectifiers interposed between said line and said devices each rectifier being made up of opposed asymmetrically conducting units and each unit being a metal having an electronically conducting compound of the metal formed thereon at a permanent and uni-laterally conducting junction, whereby the devices are never on open circuit.
21. 33. Railway traffic controlling apparatus comprising the traffic rails and traffic governing devices associated therewith arranged for operation by low voltage direct current as customary, an alternating current transmission line, and rectifiers interposed between said line and said devices each rectifier being made up of four double opposed asymmetrically conducting units and each unit being a metal having an electronically conducting compound of the metal formed thereon at a permanent and uni-laterally conducting junction whereby the devices are never on open circuit.
22. 34. Railway traffic controlling apparatus comprising traffic rails, track relays connected therewith and arranged for operation on low voltage direct current as customary, an alternating current transmission line, and transformers and rectifiers for furnishing said low voltage direct current from said line to said relays, each rectifier comprising a body consisting of a metal having an electronically conducting compound of the metal formed thereon and integral therewith, which body constitutes in and by itself a uni-directional current carrying element.
23. 35. Railway traffic controlling apparatus comprising traffic rails, track relays connected therewith and arranged for operation on low voltage direct current as customary, an alternating current transmission line, and transformers and rectifiers interposed between said line and said track rails for furnishing said low voltage direct current to the rails and so to said relays, each rectifier comprising a body consisting of a metal having an electronically conducting compound of the metal formed thereon and integral therewith, which body constitutes in and by itself a uni-directional current carrying element.

In testimony whereof I affix my signature.

LARS O. GRONDAHL.
